UNITED STATES PATENT OFFICE.

GEORGE H. HOLGATE, OF PHILADELPHIA, PENNSYLVANIA.

CARBURETER.

No. 892,726.

Specification of Letters Patent.

Patented July 7, 1908.

Application filed June 18, 1906. Serial No. 322,159.

To all whom it may concern:

Be it known that I, GEORGE H. HOLGATE, a citizen of the United States, residing at Philadelphia, in the county of Philadelphia and State of Pennsylvania, have invented certain new and useful Improvements in Carbureters, of which the following is a specification.

My invention relates to improvements in carbureters and particularly to certain new and useful improvements in a carbureter for which Letters Patent of the United States were issued to me on the twenty-seventh day of February 1906 No. 813,796.

The object of my invention is to construct a carbureter which will be adapted for heating purposes.

A further object of my invention is to so construct a carbureter that a very low grade of hydro-carbon oil may be used and thereby produce a heat at a minimum cost. To do this I provide means for heating the chamber containing the oil so that a gas of great heating power will be produced.

In carrying out my invention I employ a chamber containing an absorbent for the oil, a lamp for preheating the gas in said chamber, a central supply-pipe having a burner thereon suitable for heating and cooking purposes, means for admitting air to said chamber, means for regulating the admission of the air to regulate the quality of the gas as it passes to the burner, means for admitting air to said supply-pipe, an ignition burner located in said supply-pipe immediately above said chamber for the preliminary heating of the burner; also a housing or frame for the carbureter so that the same may be used as a gas stove for cooking and heating purposes, these together with various other novel features of construction and arrangements of parts which will be hereinafter fully set forth and claimed.

Referring to the accompanying drawings:—Figure 1. is a vertical sectional view of my improved carbureter applied as a gas stove; Fig. 2. is a horizontal sectional view as on line 2—2 Fig. 1; Fig. 3. is a horizontal sectional view as on line 3—3 Fig. 1; and, Fig. 4. is a horizontal sectional view as on line 4—4 Fig. 1.

In the drawings 1 represents a chamber which is cylindrical in form, having a top 2, a bottom 3; and a central tube 4 secured at one end to the top 2, and its other end extending to within a short distance above the bottom

3, said tube 4 is provided with openings at both ends into which tightly fits a rotatable sleeve 5. The sleeve 5 is adapted to rotate around a supply-pipe 6, said sleeve 5 fitting closely over the same. The supply-pipe 6 is rigidly held to the bottom 3 by a square bolt 7 which prevents the supply-pipe from turning. The sleeve 5 and the supply-pipe 6 are provided with apertures 8 and 9 respectively which may be made to register by turning the sleeve 5 by means of the handle 10 on the plate 11 secured to the sleeve 5. The said plate 11 is provided with apertures 13, and the top 2 of the chamber is provided with apertures 14 which said apertures 13 and 14 are brought into register when the handle 10 is turned to a position to open the apertures 8 and 9 in the sleeve 5 and the supply-pipe 6.

The chamber 1 contains absorbent material preferably formed in hollow cylinders 15, which are of different diameters so that the same may be nested, a space being left between said cylinders for the free passage of air. The cylinders are held in vertical position by perforated screens 16 and 17 so as to provide air spaces 18 and 19 above and below the absorbent cylinders. The absorbent may be of any material such as plaster-of-paris, felt, sponge, or any other material capable of absorbing a liquid, but I prefer to use a composition of plaster-of-paris and an infusorial earth.

The absorbent material is charged with gasoline, benzine, naptha, petrol or other hydro-carbon oil.

A screw cap 20 as shown in Fig. 2 is provided to cover an aperture formed in the top 2 of the chamber through which the chamber may be filled. A tube 21 is also provided at the lower portion of said chamber to draw off any excess oil which may remain in the chamber after the absorbent material has become thoroughly saturated.

Air is admitted to the chamber 1, through the openings 13 and 14 in the top 2, the air will then become charged with hydro-carbon as it comes in contact with the absorbent material and be converted into a gas.

Directly above the chamber 1, I provide an ignition-burner in the supply-pipe 6, consisting of a wire gauze cap 25. The supply-pipe has an aperture 26 formed therein which is closed by a sleeve 27 encircling the supply-pipe. The sleeve 27 has an opening 28 corresponding with the opening 26 in the supply-pipe, and the said openings may be

brought into register by turning the sleeve 27, whereby access may be had to the wire gauze cap 25.

By bringing a flame in close proximity 5 with the wire gauze cap 25 in the supply-pipe a vacuum will be created in the supply-pipe which will cause the gas to be drawn through the apertures 8 and 9 from the space 10 formed at the lower portion of the chamber 1, and the gas will continue to flow and burn at the cap 25.

The object of having the ignition-burner is to preheat the main burner 30, as the latter is such a great distance from the carbureter 15 that it cannot be lighted by a flame brought in contact with the same without preheating to create a draft which will draw the gas to the burner 30. It is desirable to make the supply-pipe as long as possible so that the 20 gas and air will become thoroughly mixed.

After the ignition-burner has been burning a few seconds the handle 10 is turned to close the air inlet apertures 13 and 14 in the chamber, and the apertures 8 and 9 in the 25 supply pipe 6, thus the supply of gas is shut off and the flame at the ignition-burner will be extinguished. The sleeve 27 is then turned so as to close the aperture in the supply-pipe 6 at the ignition-burner and the 30 handle 10 is turned to reopen the said apertures 13 and 14 in the chamber and the apertures 8 and 9 in the supply-pipe. By immediately applying a flame to the main burner 30 the gas from the carbureter will 35 burn at said burner 30.

A casing 35 is provided below the chamber 1 to receive a lamp 36 which is used to heat the chamber 1 and thereby preheat the gas and increase the quality of the same so that 40 a very low grade of oil may be used to saturate the absorbent material. The casing 35 is provided with a door 37 so that the lamp 36 will be accessible.

To regulate the quality of the gas passing 45 to the burner 30 I provide means for admitting air directly to the supply-pipe 6 through openings 40 in the supply-pipe communicating with the tube 4 which has openings 42 at the top of the same. The openings 40 in 50 the supply-pipe are closed by the sleeve 5 having openings 41 which register with the openings 40 in the supply-pipe. The openings 42 at the top of the tube 4 are closed by the plate 11 having openings 43 which register with the same. These openings are arranged so that the same will open when the handle 10 is turned to close or reduce the size of the openings 13 and 14 in the top of 55 the chamber 1 and also the openings 8 and 9

in the lower portion of the supply-pipe 6. 60 Thus if the gas is too rich with carbon the supply of air to the chamber 1 may be reduced and at the same time air is admitted directly to the supply-pipe through the openings 40 and 42, or when the gas is low 65 in carbon the openings 13 and 14 may be fully opened and the openings 40 and 42 entirely closed so that all the air admitted will pass through the chamber 1.

The carbureter is held in a housing consisting of a frame 50 supported by legs 51 which are adapted to rest on the floor. Around this frame is a casing 52 having a door 53 through which the carbureter may be removed. The casing 52 is provided with 75 a top 54 which is made in the form now generally in use in gas stoves.

Having thus described my invention I claim and desire to secure by Letters Patent:—

1. In a carbureter, the combination of a chamber, absorbent material in said chamber, a supply-pipe, a burner at the top of said supply-pipe, an ignition-burner in said supply-pipe located between said chamber and 85 said first mentioned burner, substantially as described.

2. In a carbureter, the combination of a chamber, absorbent material in said chamber, a supply-pipe, a burner at the top of said supply-pipe adapted for heating purposes, an ignition-burner in said supply-pipe located between said chamber and said first mentioned burner, and means for heating said chamber, substantially as described. 95

3. In a carbureter, the combination of a chamber, absorbent material in said chamber, a supply-pipe rigidly secured in said chamber, said supply-pipe having apertures 100 in said chamber to admit air thereto said supply-pipe having apertures formed therein for admitting air thereto, means for opening or closing said apertures, a lamp for heating said chamber, a burner at the top of said supply-pipe, a wire gauze cap in said supply-pipe located adjacent said chamber, said supply-pipe having an opening formed therein near 105 said cap, a sleeve for covering said opening, a frame to support said chamber, a casing and a top on said casing, substantially as described.

In testimony whereof I affix my signature in presence of two witnesses.

GEORGE H. HOLGATE.
